CONTAINER CLOSURE

Joseph Robinson, New York, N. Y.

Application November 28, 1944, Serial No. 565,461

2 Claims. (Cl. 285—49)

1

This invention relates to container closures. Vast war-time shipments of petroleum and petroleum products to all parts of the world; the hurried and inexperienced handling incident to the hastens and exigencies of war; temperature changes from far below zero to far above, and vice-versa; long exposure to every known kind of weather and to ocean waters, have revealed structural faults not previously evident in the closures used to close the drums in which the shipments are made. Under these conditions the expansion and contraction variables between the drum stock and the threaded insert of the closure oftens loosens the joint between them causing leakage, particularly if the content is hard-to-hold high octane gasoline. Closure plugs "freeze" in the drum heads due to corrosion. Sharp temperature changes induce "breathing" through the closure joint itself, a condition under which water on the drum head is vacuumed into the drum by contraction of the contents after substantial expansion thereof. This dilution of the contents, and plug fouling, are, of course, serious especially in the critical emergencies of war. Rust-proofing is only partially effective. The supplemental sealing device called a "seal-cap" frequently used to protect against this dilution, and against closure leakage, is not adequately dependable and has the fault of introducing another gasket making a total of three gaskets in the closure most generally used at present. Since time and temperature deteriorate gaskets, the possibility of leakage increases with gasket multiplication. The sealing gasket of the closure now most widely used is square in cross section and is quite frail. It cannot be repeatedly used but must be discarded after a single use. In replacing this gasket in the theaters of war, or elsewhere where no special application tool is available, it is almost always twisted. It is then practically impossible to make the closure joint tight, partly because this closure does not have a properly arranged seat for the gasket. While the nuisance of a twisted gasket is objectionable even for peace-time use, it is distinctly serious under war-time demands, especially when handling critical high octane gasoline. Closures employing flat gaskets do not experience this trouble, but considerably more power is required to wrench them down tight than is the case with the smaller, twistable gasket. Because of this the flat gaskets are frequently not made suitably tight and leakage results.

Among the objects of this invention are to produce a closure in which these faults are not present; a closure which is rugged and simple; which is inexpensive to manufacture; which provides "multi-service" through interchangeability with

existing closures; which does not require a seal-cap to make it tight, and which employs only a single gasket, round in cross section and free from the objections of twisting, that rests in a prepared complementary seat and may be re-used repeatedly.

Other objects and novel features of my invention will appear from the following description, in the appended claims and in the construction and arrangement of parts illustrated in the accompanying drawings in which

Figure 1 is a vertical section through my improved closure;

Figure 2 is a sectional elevation through the threaded insert A taken on approximately the line 2—2 of Figure 4;

Figure 3 is a vertical section through the housing C and the insert A inverted, showing the parts as they appear before the housing is closed in on the insert; and

Figure 4 is a bottom plan view illustrating particularly the interlocking engagement between the flat sides 11 of the insert A and the housing C when assembled.

25 My improvement comprises an internally threaded insert or ring A, die cast or otherwise formed in one or more pieces, having a flat annular face 6 between which and the threads 7 a curved bearing 8 (Figure 2) is formed. The flat or serrated edge 9 of the insert extends downwardly and outwardly from the face 6 for a distance approximating half the height of the insert, and thence curves or flares inwardly to form a shoulder or seat 10 which terminates in a plurality of flats 11, Figure 4. Stated another way, the flats 11 curve or flare upwardly and outwardly and merge into the bottom of the surface 9, and are narrowest directly below that surface. The drum head B is initially provided, as by pressing, 40 with a housing C shaped to receive the surfaces 6, 8 and 9 of the insert A, illustrated best in Figure 3 (in which view the parts are shown inverted) and by dotted lines in Figure 1. An annular bead 12 is formed around the housing, and defines the bottom thereof, and projects below the plane of the drum head B, to facilitate folding the bottom 12 of the housing tightly over the shoulder 10 of the insert into close interlocked engagement with the flats 11. The curved gasket seat 14 formed 45 in the housing fits closely in its complementary bearing 8 on the insert and extends to a point approximately in the plane of the base of the threads 7. The arrangement is such that when the insert is placed in the housing C, the gasket seat 14 engages its bearing 8 in advance of engagement between the housing and the flat face 6 of the insert, Figure 3. This arrangement as-

sures that when the bead or bottom 12 of the housing is wrapped around the shoulder 10, drawing the housing into tight engagement with the face 6, and into binding wedging engagement with the surface 8 of the insert A, the gasket seat 14 will be locked under tension in its bearing 8, thus effectively preventing at all times any vertical movement of the gasket seat with respect to its bearing 8. The housing C is, of course, wrapped under the insert A with suitable dies which force the bead 12 over the shoulder 10 with a stretching action. This technique provides "skin tight" contact between all engaging surfaces of the insert and the housing and folds or moves the bead 12 over against the flaring flats 11 into positive interlocked engagement therewith, and closes the housing permanently around the insert A.

The hollow plug D (Figures 1 and 4) of my improvement is die cast or otherwise formed, and is threaded to receive the threads of the insert A. Between its flange 15 and its threads, the plug is provided with an annular seat 16 which receives and removably retains a suitable pliable gasket E, preferably round in cross-section. When the plug is screwed into the insert A the gasket mates with the seat 14 formed in the housing C to receive it, and is compressed as the plug is wrenched down to bring its flange 15 into engagement with the flat outer face or seat 17 of the housing. Suitable lugs 18 diametrically arranged on the inner walls of the plug, and formed integrally therewith, and joined by a re-enforcement bar 19 to strengthen the bottom of the plug, afford effective wrenching means for inserting and removing the plug. Additional or substitute wrenching surface such as six or eight flats may be provided on the periphery of the flange 15, if desired.

To prevent undisclosed tampering with the contents of the drum D and to facilitate identification of its contents, a thin cap or cover F (Figure 1), painted or embossed as desired, and removable on destruction, is set over the plug and housing C and extends downward to a point near the drum head B. By means of a suitable tool, the lower edge 20 of the cap is crimped or rolled into the external annular groove 21 of the housing, which groove is formed whilst folding the bead 12 over the shoulder 10 of the insert A. This method of moving the bead into its final position not only produces the groove 21 into which to anchor the closure seal, but avoids the stresses in the metal of the drum head that would occur if the bead were folded back flat on itself at this point. The groove also receives a tie ring sometimes used to tag the drum and identify its contents.

The foregoing improvements produce a simple, rugged closure that is leak proof and corrosion proof in which the plug D will not "freeze"; a closure that is easy to insert in the drum head and which cannot loosen or rotate therein, and which provides "multiple-service" because interchangeable with the replacement parts of existing closures. Through its single joint formed by the round cross section gasket E and its smooth conforming seat 14-16, no water on the drum head can be vacuumed into the drum. Content dilution cannot therefore occur. The tight wedging action of the tapered surface 8 against the housing C as on the insert A is forced to final assembly, and the fact that the harder the plug D is wrenched down the tighter the insert is friction locked against the walls of the housing, assure positively against the insert loosening or turning in the drum head. While the round cross sec-

tion gasket has several advantages and is preferred, the square cross section gasket, when mounted in seats 14-16 (Figures 1 and 3), and the flat gasket when mounted on seat 17 (same figures) make as good or better a joint with the present invention as when used in the closures to which they belong. Expansion variables do not adversely affect my improvement due to its rugged construction and to the compensating 10 spring tension against the insert A placed in the housing C when closing the housing over the insert. I have shown the insert made in one piece, but obviously it may be formed in sections, 15 or curled from profiled stock in which the thread has been rolled or milled (or is later tapped) this because the joint between the housing C and the insert A are both sealed by the single gasket E and do not depend for tightness upon any other seal. I am aware that to those skilled in the art other modifications will occur that do not depart from the spirit or scope of my invention. I, therefore, desire not to be limited to the specific 20 embodiments herein disclosed.

What I claim is:

25 1. In a closure receiving ring-like insert for a metal container, in combination, a wall of the container having an opening defined by an outwardly extending sleeve, the outer end portion of the sleeve having an annular inwardly directed 30 right-angle flange formed with a depressed marginal gasket receiving seat, and an externally flanged ring-like insert disposed in said sleeve and having an annular depression formed to receive the depressed seat portion of the sleeve, the outer end portion of the sleeve being preformed 35 so that the inner face of the wall defining the depressed marginal gasket receiving seat is spaced from the opposite inner face of the sleeve a distance less than the thickness of the outer end 40 portion of the ring-like insert, whereby to provide tensioned gripping engagement between the insert and the sleeve when the inner end portion of the sleeve is forced inwardly beneath the external flange of the insert to force the insert into 45 the preformed outer end of the sleeve and to form skin-tight engagement between all the mating surfaces of the parts.

2. In a closure receiving ring-like insert for a metal container, in accordance with claim 1, 50 wherein the external face of the insert beneath the flange thereof is provided with a plurality of upwardly extending outwardly flaring flats which merge into the bottom of said external flange and which co-act with said sleeve to prevent relative 55 rotation between the insert and the sleeve when the inner end portion of said sleeve is forced inwardly against said flats.

JOSEPH ROBINSON.
